US00D777849S

(12) **United States Design Patent** (10) Patent No.: **US D777,849 S**
Jones et al. (45) Date of Patent: ** Jan. 31, 2017

(54) **BENCH PRESS SAFETY ATTACHMENT**

(71) Applicants: **Geoff Ryan Jones**, Fullerton, CA (US);
Casey Thomas Shine, Placentia, CA (US)

(72) Inventors: **Geoff Ryan Jones**, Fullerton, CA (US);
Casey Thomas Shine, Placentia, CA (US)

(**) Term: **15 Years**

(21) Appl. No.: **29/528,561**

(22) Filed: **May 29, 2015**

Related U.S. Application Data

(63) Continuation of application No. 13/398,689, filed on Feb. 16, 2012, now Pat. No. 9,132,313.

CLAIM

The ornamental design for a bench press safety attachment, as shown and described.

DESCRIPTION

FIG. 1 is a perspective view of a bench press safety attachment, showing our new design.

FIG. 2 is a front view thereof.

(Continued)

FIG. 3 is a rear view thereof.
FIG. 4 is a top view thereof.
FIG. 5 is a bottom view thereof.
FIG. 6 is a side view thereof; and,
FIG. 7 is an opposite side view thereof.
